DESIGN FOR A CLOCK FACE

Walter D. Teague, Forest Hills, N. Y., assignor
to Warren Telechron Company, a corporation
of Maine

Application October 28, 1937, Serial No. 72,473

Term of patent 14 years

To all whom it may concern:

Be it known that I, Walter D. Teague, a citizen of the United States, residing at Forest Hills, in the county of Queens, State of New York, have invented a new, original, and ornamental Design for a Clock Face, of which the following is a specification, reference being had to the accompanying drawing, forming a part thereof.

Fig. 1 is a front view of a clock face showing my new design, and Fig. 2 is a side view thereof on a reduced scale in comparison with the disclosure in Fig. 1.

I claim:

The ornamental design for a clock face, as shown and described.

WALTER D. TEAGUE.
